UNITED STATES PATENT OFFICE.

WILLIAM C. SMITH, OF PHILADELPHIA, PENNSYLVANIA.

THILL-TUG.

No. 920,679.

Specification of Letters Patent.

Patented May 4, 1909.

Application filed December 26, 1907. Serial No. 408,134.

To all whom it may concern:

Be it known that I, WILLIAM C. SMITH, citizen of the United States, residing at Philadelphia, in the county of Philadelphia and State of Pennsylvania, have invented new and useful Improvements in Thill-Tugs, of which the following is a specification.

My invention pertains to thill tugs; and it contemplates the provision of a neat, strong and durable thill tug embodying such a construction that its major portion may be economically formed of short and consequently inexpensive pieces of leather.

To the attainment of the foregoing end the invention consists in a thill-tug made up of a thill-loop of leather, adapted for the connection of a pad-strap and having an opening in its lapped and connected portions, a buckle, a box-loop, a reinforcing strap, of leather, passed through the said opening in the thill-loop and carrying the buckle and the box-loop and having its ends arranged close together and against the lower end of the thill-loop, a metallic plate riveted to and connecting the adjacent end portions of the reinforcing strap, and a metallic eye held by said plate and carrying a belly band billet.

In the drawings accompanying and forming part of this specification: Figure 1 is a perspective view of my novel thill-tug. Fig. 2 is a vertical section of the same with the belly band billet in edge elevation.

Similar letters designate corresponding parts in both views of the drawings, referring to which:

A is the thill-loop of my novel device, which as before stated is made of leather. The said loop is provided in its lapped and connected portions *a* *b* with an opening *c*, and the portion *a* is carried above the portion *b* and is provided with an opening *d* for the passage of a pad strap (not shown). The connection of the said portions *a* and *b* is preferably effected through the medium of a rivet *e*.

B is the reinforcing strap also of leather. The said strap B is looped through the opening *c* of the thill-loop A, and is equipped with a buckle C and a box-loop D; the buckle C being arranged as shown with its tongue extending through an opening *f* in strap B, and the box-loop D being arranged to receive the said strap to which it is fixedly connected, preferably by rivets *g*, Fig. 2. The ends of the strap B are brought together

below the thill-loop A, and are retained in said relation through the medium of a curvilinear metallic plate E. This latter is fixedly connected, preferably by rivets *h*, to the end portions of the strap B, and is channeled at *i* to receive an eye F through the medium of which the belly band billet G is connected.

It will be gathered from the foregoing that both the thill-loop A and the reinforcing strap B may be formed of short and inexpensive pieces of leather, and that this contributes materially to the cheapness of the thill-tug. It will also be gathered that notwithstanding the formation of the thill-loop A and the reinforcing strap B of small pieces of leather, the thill-tug as a whole is neat in appearance and is well adapted to withstand the rough usage to which such devices are ordinarily subjected. In this latter connection it will be manifest that the curvilinear metallic plate E which connects the end portions of the reinforcing strap B together and also effects connection between the eye F and the said strap B, serves the additional function of retaining the shape of the tug at the point where the thill passes through the same and also serves to reinforce the portions of the thill-loop A and strap B which, when the device is in use, rests between a thill and the said plate E.

It will be further manifest from the foregoing that the arrangement of the curvilinear metallic plate E around the bottom of the thill loop is materially advantageous, particularly when one person is ungearing a horse, this since it will not bind but will allow the thill or shaft to slide out of the loop freely. This will be better appreciated when it is remembered that while the person holding a thill or shaft can keep the same free on the side of the horse where the person is positioned, it frequently occurs that the tug on the other side of the horse binds on the thill or shaft and pulls the harness off the horse's back.

In practice, the buckle C as well as the plate E and the eye F will be japanned or otherwise embellished with a view of enhancing the finished appearance of the thill tug as a whole.

It will be further gathered from the foregoing that not only the thill loop A and the reinforcing strap B, but also the belly band billet G may be formed of a short and consequently inexpensive piece of leather with a

view of rendering the production of the thill
tug inexpensive.

I am well aware of Patent No. 291,315
granted to Evans *et al.*, and Patent No. 560,206
5 granted to one Gleckner, and I therefore
make no claim to the devices shown therein.

What I claim and desire to secure by Let-
ters Patent, is:

The herein described thill tug consisting
10 essentially of a thill loop formed of a single
piece of leather and having lapped and con-
nected upper end portions and an opening in
said portions, a reinforcing strap formed of a
single short piece of leather and passed
15 through the said opening in the lapped and
connected portions of the thill loop and
snugly surrounding said thill loop and having
its ends disposed together at a point below

the lower portion of the thill loop, a buckle
and a box loop carried by the said reinforcing
20 strap, a billet or strap provided with a metal-
lic eye, a curvilinear metallic plate arranged
under and against the end portions of the
reinforcing strap and having a channeled
25 portion receiving the eye on the billet or
strap, and rivets connecting the end portions
of the curvilinear plate to the end portions of
the reinforcing strap.

In testimony whereof I have hereunto set
my hand in presence of two subscribing wit-
nesses.

WILLIAM C. SMITH.
